UNITED STATES PATENT OFFICE.

JOHN H. FELMLEE, OF PITTSBURG, PENNSYLVANIA.

WRAPPING-MACHINE.

SPECIFICATION forming part of Letters Patent No. 699,750, dated May 13, 1902.

Application filed April 30, 1901. Serial No. 58,148. (No model.)

To all whom it may concern:

Be it known that I, JOHN H. FELMLEE, a citizen of the United States, residing at Pittsburgh, in the county of Allegheny and State of Pennsylvania, have invented certain new and useful Improvements in Wrapping-Machines; and I do declare the following to be a full, clear, and exact description of the invention, such as will enable others skilled in the art to which it appertains to make and use the same, reference being had to the accompanying drawings, and to the letters of reference marked thereon, which form a part of this specification.

This invention relates to new and useful improvements in machines for wrapping caramels and other articles; and it consists in the provision of means for automatically feeding the wrapping-paper forward, cutting same to a certain measured length, and of mechanism for feeding the article to be wrapped forward to a position over the wrapping-paper and of folding or wrapping the paper about the article and depositing same in readiness to be packed in suitable boxes for shipment.

The invention consists in the provision of various combinations of parts, which will be hereinafter more fully described and then specifically defined in the appended claims, and is clearly illustrated in the accompanying drawings, which, with the letters of reference marked thereon, form a part of this application, and in which drawings similar letters of reference indicate like parts throughout the several views, in which drawings—

Figure 1 is a side elevation of my machine, parts of the inclosing frame being removed to better disclose the various parts of the mechanism. Fig. 2 is an elevation of the opposite side of the machine with parts of the frame being removed. Fig. 3 is a front elevation with parts of the frame being shown in section. Fig. 4 is a vertical sectional view taken on line 4-4 of Fig. 3. Fig. 5 is a top plan view of the machine. Fig. 6 is a top plan view in detail of the folding-table or slotted trough along or through which the article being wrapped passes while the last flaps of the wrapper are being folded. Fig. 7 is a detail view in perspective of the means employed to hold the caramel or other article to be wrapped preparatory to its being depressed

onto the wrapping-paper. Fig. 8 is a detail in perspective of one of the end-flap-folding members. Fig. 9 is a face view of the folding member shown in perspective in Fig. 8. Fig. 10 is a detail view showing the lower pivoted ends of the outwardly-swinging arms, which carry at their upper ends the end-folding members. Fig. 11 is a detail view of the knife which cuts off a measured length of wrapping-paper. Fig. 12 is a detail view showing the article to be wrapped as having been deposited on the wrapping-paper and in readiness to be depressed in the first step of the folding of the wrapping-paper. Fig. 13 is a detail showing the second step of the wrapping in which the end flaps are folded up against the opposite edges of the article. Fig. 14 shows the third step in the folding, in which the opposite flaps are shown as folded one over the other. Fig. 15 illustrates the fourth step in the folding operation. Fig. 16 is a detail showing the opposite end flaps being folded against the end of the article, and Fig. 17 shows the article on the folding-table in readiness to be fed forward to have the last flaps folded by the flaps being forced into the inclined slots shown in said table.

Reference now being had to the details of the drawings by letter, A designates the frame of the machine, which may be suitably housed and which supports the operative features of the invention. In the lower part of the frame is suitably journaled a driving-shaft B, to which power may be applied from any source, which may be transmitted to the pulley B', mounted on said shaft. Keyed or otherwise secured to rotate with said shaft is a cam-wheel C, having a cam C' on its periphery, and on the inner face of said cam-wheel is a segment-cam C². (Shown plainly in elevation in Fig. 4 of the drawings, also in Fig. 2.) This segment-cam extends substantially one-third the distance about the face of the cam-wheel and carries a pin or lug C³.

D designates the folding-table on which the articles to be wrapped are deposited and along which the partially-wrapped article is advanced during the folding of the last flaps, and E the trough through which the articles to be wrapped are fed to a position from which one by one the articles are taken through the machine to receive the wrappers.

The wrapping-paper is reeled on a shaft F, journaled at one side of the frame, and is fed between the feeding-rollers G and G', the former of which rollers is journaled in stationary bearings, while the roller G' is journaled in the plates G², having their upper ends inverted-L-shaped to engage over the upper ends of the upright portions of the frame. Set-screws G³ are passed through threaded apertures in said inverted-L-shaped ends, and the ends of said screws bear against the tops of said upright portions of the frame, as seen clearly in Fig. 3 of the drawings. By this adjusting means the feed-roller G', which is journaled in said plates G², may be slightly raised or lowered to regulate the frictional contact of said roller G' against the wrapping-paper beneath. Said feed-roller has a bevel gear-wheel G⁴, keyed to rotate with its projecting end, which gear-wheel is in mesh with a bevel gear-wheel G⁵, Fig. 2, the latter wheel G⁵ being keyed to rotate with the diagonally-disposed shaft G⁶, the upper end of which is journaled in the bracket G⁷, while the lower end of said shaft G⁶ has mounted to rotate therewith a bevel gear-wheel G⁸, which is in mesh with a bevel gear-wheel G⁹, which latter is keyed on the main driving-shaft B, Fig. 3. From this construction it will be observed that the feeding-roller G' is constantly in motion while the machine is in operation, while the roller G has an intermittent rotary movement, said wheel G being idle for a moment in each revolution to allow the wrapping-paper to be cut off. Upon examination of Fig. 4 of the drawings it will be seen that a portion of the circumference of the roller G' is recessed, as at g, the bottom wall of said recessed portion being on the arc of a circle of smaller diameter than the main body portion of the roller, so that when said recessed portion of the roller is presented adjacent to the paper beneath a slight space will intervene between the paper and the reduced or recessed portion, and as there will be no frictional contact between the roller G' and the paper while this recess is passing adjacent to the paper the latter will remain stationary. The curved or convexed bottom of this recess serves another purpose, however, in that it has a tendency to hold the wrapping-paper from doubling or flapping up from the under roller G while the paper is stationary.

The paper after being measured off a sufficient length for the wrapper, which is determined by the circumference of the feeding-surface of the roller G', passes through slots H in the plates H' and H², which are mounted horizontally on the top of the frame, and between each of said plates H' and H² is a slight space of sufficient width to allow the cutting-knife I to pass between to cut off the wrapping-paper the proper length. Said cutting-knife is pivoted at I' to an angle-iron I², Figs. 3 and 11, said angle-iron being held to the frame of the machine. To the knife is pivoted at J one end of the rod J', the other end

of which rod has pivotal connection with the end of the rod J², which is pivoted at its other end to the pin J³, Fig. 2, which pin is secured to the frame of the machine. A lug J⁴ on the circumference of the wheel J⁵ on the main driving-shaft at each revolution is adapted to trip the free end of the rod J² and depress the latter, which will cause the knife to be thrown down through the space between said plates H' and H². After the lug J⁴ passes the free end of the rod J² the spring J⁶, fastened at one end to the bar J², its other end to the frame, will cause the knife to swing back to its upright position, as shown in Fig. 3. A tension device I⁵, Fig. 4, is provided, comprising a flexible plate bent upon itself and designed to be held over the table I⁶, the inner end of which plate is adapted to bear with slight frictional pressure against the strip of paper to hold the same from drawing back toward the reel.

To receive the forward end of the wrapping-paper which is fed through between the feeding-rollers and supports same over the passage-way through which the article to be wrapped is depressed, I provide a reciprocating plate K, which is mounted on the top of the frame and provided with two blades K^x and K^y, the former of which is slightly upwardly bent, so that it will not offer any obstruction to the end of the wrapping-paper which is fed between the blades. This reciprocating plate is actuated by means of the lever K², which is pivoted on the pin K³, Figs. 1 and 4. The upper end of this lever K² has a contracted end k, which passes through an aperture in said plate K, and as the lever K² is rocked on its pivot the plate is caused to reciprocate. The lever K² is actuated by means of the blade-folding-actuating lever L, Fig. 1. Said lever L is pivoted at L' to the frame, and a spring L², mounted on said pin L', has one end secured to or bearing against a pin L³ on the lever L, while the other end of the spring bears against the frame in which the cross-head M reciprocates. This spring serves to hold the levers K² and L normally in the positions shown in Fig. 1.

The lower end of the lever L is concaved, as at l, Figs. 2 and 4, and is disposed in the path of the segment-cam C², so that at each revolution of the wheel C said segment-cam will strike against and tilt the lever L. The object of recessing the lever L at l is for the purpose of allowing said lever to return to its normal position quickly after the cam-segment C² has tilted the lever. Said cam first contacts with the lever L at the lower end of the latter, and the opposite edge of said segment-cam is the last portion thereof to leave the lever and rides in said recessed portion just before leaving the lever. If the edge of the lever were straight, it will be readily understood that the lever would be slower in returning to its normal position, too slow, in fact, to actuate the plate K at the proper time, also the side-folding blade, and have the

latter accomplish its work in advance of the folding-blade on the opposite side of the passage-way containing the article being folded. The upper end of said lever L is slotted and loosely receives the pin L⁴, which is disposed in the slot K⁵ of the lever K². This pin L⁴ is secured to the folding-blade N, which reciprocates horizontally as the lever L is tilted and is thrown forward a sufficient distance to fold over the second of the upright flaps. To the under face of said folding-blade N is secured a spring-flap N', the forward end of which spring is fastened to the inner end of said blade, while the rear end, which is free, is slightly bent downward toward the folding-table D, and against this spring, as well as against side springs N², Fig. 4, at right angles to the opposite longitudinal edges of the table D, the wrapped articles are held while being forced out through the trough formed by the springs on three sides and the table as a bottom. Said springs N² are vertically disposed on opposite sides of the passage-way down through which the articles to be wrapped pass to steady the same, as they are being depressed onto the folding-table.

The articles to be wrapped as they are fed singly to a position over the passage-way down through which they are depressed with the wrapping-paper beneath, the articles being forced forward by a succeeding article crowding the one in front of it forward, are held suspended over the wrapping-paper for a moment after the slotted plate K has been withdrawn, said swinging shoe O, which is angled at its lower end and at its upper end is pivoted to the yoke O², secured to the upper end of the frame of the machine. This yoke is bent upon itself at its longitudinal center, with a space intervening between its arms, into which space said foot is allowed to swing, so that its lower end will be free from the article to be wrapped and be out of the way of the arms which carry the article, with the wrapper, down to the wrapping-table beneath. Mounted on the pivotal pin O' is a plate O³, which carries a pin O⁵, which passes through a slot in one arm of said yoke and has its inner end secured to the shoe O, and the outer edge of said plate O³ is disposed at an inclination and slightly in advance of the forward end of said shoe, for a purpose which will hereinafter appear.

Secured to the outer face of the cam C is a pin C⁵, which has a sliding movement in the elongated slot C⁶ of the lever C⁷, which latter is pivoted at C⁸ to the frame. To the lever C⁷ is pivoted the lower end of the pitman P, the upper end of which is pivoted to the sliding plate M⁵, which has a sliding connection with the head M. This cross-head reciprocates in the frame, being confined in grooves therein by means of the gibbs M². To the outer face of said cross-head is fastened an ear M³, which carries a pin M⁴, on which the lower angled end of the arm Q is pivoted. On the same pin M⁴ is pivoted one end of

the link Q', Fig. 10, said link being also engaged by a pin Q³, which passes through the lower end of the arm Q⁴, thus causing the link and arm to tilt together. The lower end of the arm Q is concaved, as at Q³, and has a frictional bearing against the convex portion of the end of the second arm Q⁴. Shoulders Q⁵ on the meeting ends of said arms serve to limit the inward throw of the upper portion of said arms, while a lug Q⁶ serves to limit the outward throw of arm Q, and the slotted angle-iron Q⁷, Fig. 10, serves to limit the outward throw of the arm Q⁴. The free end Q⁸ of the link Q', Fig. 1, passes through a recess in the plate M⁵, and as the sliding plate M⁵ when at its highest limit begins to move downward a short distance independent of the cross-head, said distance being limited by the end of the slot M⁶ coming into contact with the pin n, carried by the cross-head, the two arms will be thrown toward each other. The upper ends of these arms are provided with plates R, which are disposed at right angles to the length of the arms, and when at their inner limits are designed to engage over the top of the article about to be wrapped. The sliding plate M⁵, to which the upper end of the pitman is pivoted, is slotted at its lower end, as at M^x, and a headed screw m³ holds the lower end of said plate to the cross-head and allows a limited play to said plate.

M⁸ is a spring, one end of which is fastened to the frame of the machine, while the upper free end bears against the inner face of the cross-head with sufficient frictional pressure to hold the cross-head suspended while the sliding plate M⁵ is traveling a distance equal to the length of the slot M⁶ in the upper end thereof. The cross-head, it will be noted, remains stationary at its highest limit for a moment, during which interval the end-folding blades S are allowed time to swing in against the ends of the article being wrapped and engage behind the guide-plates S' on either side of the central upright portion of the frame of the machine. Pivoted to each plate S', each of which supports a folding-blade S, is a folding member S², a detail view of which is shown in Fig. 8, and each member S² has a pin S³ at right angles to the length of the member, Figs. 8, 9, and 15. This pin is held to its forward limit by means of a spring S⁴, secured to the folding-blade S and bearing against the pivoted end of said member. The outward throw of the folding member is limited by the shouldered portion S⁵ coming in contact with the pin S⁶.

The lower end of each folding-blade S, each of which blades is mounted on a plate S', adjustably held at different heights on the arms Q and Q⁴, is provided with a recess, one edge of which has a cam projection T near the upper end of the recess, while the other edge of the slot is gradually curved, as seen at T', Fig. 16. These curved edges of the recess in the blade S are for the purpose of folding the opposite edge flaps of the wrap-

per, and the reason of providing the abrupt curve or cam on one edge of the recess is to fold in one flap slightly in advance of the opposite one. The cam projection first coming in contact with one flap will begin to fold it before the edge of the recess with a gradual curve reaches the opposite flap, so that the two edge flaps will be folded without interference with each other. In order to throw the folding member S^2 outward after it has folded the two horizontal flaps and not to be in the way to interfere with the folding in of the edge flaps, an inclined projection or angled plate T^5 , Figs. 1 and 2, is provided, which is secured to the frame with its outer inclined end in the path of the pin S^9 , which pin strikes against the rounded end of said angle-iron and throws the lower free end of the folding member S^2 outward at the moment the opposite edge flaps are being folded. It will be observed that while the flaps are being folded by the plates S the plates R at the ends of the arms Q and Q' are in engagement with another article to be wrapped and drawing the same down to the folding-table to take the place of the preceding article being wrapped, which latter, however, is pushed out of the path of the following article by a plunger. As an edge of one of said plates R comes in contact with the inclined edge of the member O^3 the shoe will be thrown back into the yoke and the article will be deposited on the wrapping-paper preparatory for its depression onto the folding-table.

V designates a blade-actuating lever which is pivoted at V' , and a spring V^2 , carried by said pin V' , has one end bearing yieldingly against the gib for the cross-head, while its other end bears against a pin V^3 on the lever V and serves to hold the lever V in the position shown in Fig. 1 of the drawings. The lower inner edge of said lever V is disposed in the path of the cam C' , and at each revolution of the wheel C said lever is tilted, and the upper end of the lever is slotted, as at V^4 , and receives a lug V^5 , which is secured to the horizontally-folding blade V^6 . (Shown in Fig. 4.) To the upper edge of said lug V^5 is fastened one end of a spring-flap V^7 , which spring carries at its forward end a pin V^8 , the ends of which are passed through the inclined slots V^9 in the upright portion of the frame, and as said folding-blade V^6 is driven forward the forward end of the spring will be depressed, and through its connection with said blade the latter will be yieldingly held down as the blade is driven forward, thus allowing the blade to yield slightly should an article being wrapped happen to be of a greater thickness than an average article.

All of the flaps of the wrapper with the exception of the last or final flap having been folded by the mechanism described, the plunger W , which is mounted on the table D , is driven forward by means of the lever W' , Fig. 4, which lever is mounted to tilt on the pivotal pin w and normally held in the posi-

tion shown in Fig. 4 by means of the spring W^2 , which is carried by the pin W^3 , one end of said spring bearing against the edge of the lever W' , while its other end bears against the frame of the machine. The upper end of the lever W' is contracted and passes through an aperture in the bottom of said plunger, whereby as the lever is rocked on its pivot W^1 the plunger will be driven forward and returned to its starting position. The lower end of said lever W' is pivoted to the link W^4 , which in turn is pivoted to the trip-arm W^5 , which is pivoted at W^6 to the frame of the machine. The lower end of the trip-arm W^5 projects a short distance beyond its lower pivotal point, and said projecting end is disposed in the path of the pin C^3 , whereby at each revolution of the segment-cam carrying C^2 said pin said arm is tripped, and through its connections with the plunger the latter is driven forward gradually, and after the projecting end of said arm leaves the pin C^3 the arm will quickly return to its normal position, and in so doing the plunger will under the influence of the spring W^2 return to its starting position. Said plunger is slotted in from its outer or wrapper-engaging end, as shown at W^7 , Fig. 3, to receive the lower end of the spring W^8 , the upper end of which spring is secured to the frame directly underneath the slotted plate H^2 . This spring W^8 is provided for the purpose of holding the articles being wrapped from falling down on the folding-table and yields slightly as the depressing-arms are pulling the article partially wrapped down into a position to have the final flaps folded. As the plunger forces the article forward on the table for the purpose of causing the last flaps to be folded said last flaps, which are downwardly disposed and slightly curved, enter the two diagonally-disposed slots X and X' , one being slightly in advance of the other and projecting outward over the opposite sides of the table, forming wings to guide the end flaps, so that the last flap on one end will be folded in advance of the other and folded underneath the bottom of the article. After the articles are wrapped they are pushed out through the trough by the succeeding articles.

In operation the paper is fed forward by the feed-rollers, and is cut by the knife through the medium of the pivoted rods J' and J^2 , the latter of which is tripped by the lug J^4 . The slotted member K is pushed forward to receive and support the wrapping-paper, while the latter passes over the space down through which both the paper and article to be wrapped are depressed. As the cam-wheel C rotates, so that the cam C' will contact with the lower edge of the lever V , and, tilting the latter, the folding-blade V^6 will be thrown forward and fold one of the upright flaps. (Shown in Fig. 13.) Aftersaid flap is partially folded the segment-cam C^2 on the opposite face of the wheel C will contact with the lower end of the lever L and commence to tilt same, and as it tilts the folding-blade N

will be thrown forward to fold the second upright flap, Fig. 13. As the pin C^5 begins to raise the lever C^7 , to which the pitman is pivoted, the latter will impart a longitudinal motion to the sliding plate M^5 , which will cause the link Q^8 to tilt the arms Q and Q^4 , so that their upper ends will be thrown outward as they rise. During this movement, owing to the pin C^5 being at the inner end of the slot C^6 , the movement of the pitman will be accelerated, and the speed of the pitman will be somewhat slackened on its downward throw as the pin C^5 changes its pivotal center to the opposite end of said slot C^6 . When the pitman reaches its highest throw and commences to descend, it will be observed that the sliding plate M^5 will have a slight downward movement independent of the cross-head, the latter remaining stationary for a moment, sufficiently only to allow the depressing-arms Q and Q^4 to be thrown toward each other and into vertical positions, with the plates secured at their upper ends directly over the ends of the article to be wrapped. As said arms are thrown inward on the downward movement of the sliding plate M^5 , actuating the link Q^8 , which draws the arms together, the folding-blade S , one on each side of the central portion of the frame of the machine, will engage behind the guide-plates S' . By the time the sliding plate M^5 reaches its lowest limit with relation to the cross-head on which it is mounted and when the upper end of the slot M^6 contacts with the pin m the cross-head will commence to descend with the sliding plate, and as the edge of the slotted or recessed blade having the cam T contacts with one of the edge flaps it will be partially folded before the opposite flap is folded in by the edge T' , which is gradually outlined. Previous, however, to the folding of the opposite edge flaps the upper flaps are folded down by the member shown in Fig. 15 of the drawings, which member engages the flaps as the blade S commences to descend. As the pin S^9 contacts with the rounded edge of the angle-iron T^5 and throws the lower end of the folding member S^2 outward, so that it will not interfere with the folding in of the opposite edge flaps, by the time the edge flaps are folded in the swinging folding member S^2 will have passed over the angle-iron T^5 and resume its normal position. After the top and edge flaps have been folded the plunger W is driven forward and forces the article, with its downwardly-extending remaining flaps, one at each end thereof, forward, and said flaps enter the slots X and X' , which are arranged one in advance of the other, and the last flaps are folded under the bottom of the article, and the succeeding articles will force the wrapped ones out through the trough, from which they may be fed to an apparatus for packing same in boxes for shipment.

In this application I make no claim for a feeding mechanism for conveying the articles

to be wrapped, but have shown in Fig. 2 a belt Z , on which a line of caramels or other articles to be wrapped may be fed into the trough. A sufficient forward pressure will be exerted on the line of articles in the feeding-trough to advance same one by one to a position above a severed piece of paper.

What I claim is—

1. A wrapping-machine, consisting of a frame having folding mechanism, a wrapper-feeding device, a depending shoe for temporarily holding an article to be wrapped, and means for swinging the shoe from underneath said article preparatory to its being wrapped, as set forth.

2. A wrapping-machine, consisting of a frame and folding apparatus, a wrapper-feeding device, a depending swinging shoe on which an article is fed and temporarily held, arms designed to depress the article and wrapping-paper onto a folding-table, and means actuated by one of said arms, for depositing the article to be wrapped on the wrapping-paper by withdrawing said shoe, as set forth.

3. A wrapping-machine, consisting of a frame and folding mechanism, a wrapper-feeding device, a depending swinging shoe mounted over the wrapping-paper, and designed to temporarily hold the article to be wrapped over the paper, arms for engaging the article, one of said arms adapted to swing said shoe from under the article to be wrapped, and means for depressing the article and paper beneath same onto a folding-table, as set forth.

4. A wrapping-machine consisting of a frame and folding mechanism, an intermittent wrapping-paper feeder for advancing the paper to a position on which an article is deposited, means for cutting the wrapping-paper a measured length, a yoke secured to the frame, a swinging shoe pivoted thereto, and having an angled end adapted to temporarily support the article to be wrapped, the pivoted arms for engaging the article and depressing same with the wrapping-paper onto a wrapping-table, one of said arms designed to throw the shoe back to free the article as the arms approach each other, as set forth.

5. A wrapping-machine, consisting of a frame and folding mechanism, an intermittent wrapping-paper-feeding mechanism for advancing a piece of paper to a position to receive an article to be wrapped, means for cutting the paper a measured length, a yoke secured to the top of the frame, a swinging shoe having a projection designed to temporarily support the article to be wrapped, a plate pivoted to swing with said shoe, and arms having angled ends which engage and depress the article to be wrapped, one of said arms designed to contact with and swing said plate and the shoe secured thereto backward to free the shoe from the article, as set forth.

6. A wrapping-machine, consisting of a frame and folding mechanism, an intermittent wrapping-paper-feeding mechanism for

advancing the paper to a position to receive an article to be wrapped, means for cutting the paper to a measured length, a yoke secured to the frame, a shoe, having an angled 5 projection, and pivoted within said yoke, a plate mounted to swing with said shoe, and guided by a pin working in a slot in one of the arms of the yoke, the edge of said plate being inclined, the pivoted arms with plates 10 secured to the ends thereto which are adapted to engage over the article to depress same onto a wrapping-table, one of said arms adapted to contact with said plate and swing same together with said shoe rearward to release the 15 article and deposit same on the wrapping-paper, as set forth.

7. A wrapping-machine, comprising a frame and folding mechanism, an intermittent wrapping-paper-feeding mechanism, for advancing 20 the paper to a position to receive an article to be wrapped, a reciprocating paper supporting and guide plate, means for operating same, a swinging shoe for temporarily supporting the article to be wrapped over the 25 wrapping-paper which has been cut to a measured length, and mechanism for swinging the shoe rearward and for operating said guide-plate, as set forth.

8. A wrapping-machine comprising a frame 30 and folding mechanism, paper-feeding means, a reciprocating plate mounted on the frame of the machine and having two blades K^x and K^y spaced apart, a tilting lever engaging said slotted plate, and adapted to reciprocate the 35 same, and means for tilting said lever, as set forth.

9. A wrapping-machine, comprising in combination with the frame, the paper-feeding mechanism, means for cutting the paper, 40 swinging arms which are adapted to automatically grip an article which has been deposited upon the wrapping-paper, means for operating said arms and depress the same with the wrapping-paper, and means for folding 45 the opposite longitudinal edges of the wrapping-paper about an article resting on a folding-table, as said swinging arms are raised to their highest position, as set forth.

10. A wrapping-machine, comprising in combination with the frame of the machine, 50 means for feeding the paper to a position to receive an article to be wrapped, pivoted and vertically-reciprocating arms adapted to grip the article which has been superimposed upon the wrapping-paper and depress the same 55 with the wrapping-paper, means for operating said arms, a wrapping-table, and means for folding one edge of a wrapping-paper resting on said table on which an article to be wrapped 60 rests, slightly in advance of the opposite flap, said folding being effected in the upward throw of said reciprocating arms.

11. In a wrapping-machine, the combination 65 with the frame, reciprocating pivoted arms, which are adapted to engage and depress an article to be wrapped, which has been superimposed upon the wrapping-paper, means

for operating said arms, a stationary wrapping-table, horizontally-movable folding-blades mounted above said table, and levers 70 which are adapted to actuate said blades, one in advance of the other, as said swinging arms are raised to depress a following article to be wrapped, as set forth.

12. A wrapping-machine, comprising in 75 combination with the frame, vertically-movable swinging arms, which are adapted to engage and depress an article to be wrapped, which has been previously superimposed upon a piece of wrapping-paper, means for operating said arms, a driving-shaft and connections between said shaft and the swinging arms for operating the latter, folding-blades adapted to be actuated, one in advance of the other, as said arms are raised to their highest positions, 80 as set forth.

13. A wrapping-machine, comprising in combination with the frame, an operating-shaft, a reciprocating cross-head, pivoted and swinging arms carried by said cross-head, connections between said shaft and cross-head 90 for operating the latter, and means for tilting or swinging said arms as the cross-head reciprocates.

14. A machine for wrapping articles, comprising in combination with the frame, a driving-shaft, a cam-wheel mounted thereon, a cross-head and connections between same and said cam-wheel for reciprocating the cross-head, folding-blades, which are driven forward by said cam-wheel as the cross-head rises, pivoted and swinging arms carried by the cross-head, and adapted to be thrown outward as the cross-head is raised, and means for throwing the arms toward each other as 105 they approach their highest position, as set forth.

15. A machine for wrapping articles, comprising in combination with the frame, a driving-shaft, cam-wheel mounted thereon, a reciprocating cross-head, horizontally-disposed folding-blades, which are driven forward by the cam-wheel, as said cross-head rises, pivoted arms mounted on said cross-head, and end-folding blades carried by said arms, as 115 set forth.

16. A machine for wrapping articles, comprising in combination with the frame, a driving-shaft and cam-wheel rotating therewith, a reciprocating cross-head, connections between same and said driving-shaft, the side-folding flaps actuated by said cam-wheel, the pivoted arms carried by the cross-head, and means for operating said arms as the cross-head reciprocates, an edge-folding blade secured to each arm, adapted to fold the opposite edge flaps of the wrapper, as said arms descend, as set forth.

17. A machine for wrapping articles, comprising in combination with the frame the 130 driving-shaft, the cam-wheel rotating therewith, cross-head and connections between same and said cam-wheel, the side-folding blades actuated by said cam-wheel, the piv-

oted arms carried by the cross-head and means for tilting said arms as the cross-head reciprocates, an edge-flap-folding blade secured to each of said arms, and a pivoted folding member carried by each arm, as set forth.

18. A wrapping-machine, comprising in combination with the frame, the driving-shaft, cam-wheel rotating with said shaft, horizontally-movable folding-blades and levers actuated by the cam-wheel for operating the same, a reciprocating cross-head, pivoted arms carried thereby, and adapted to be tilted as the cross-head reciprocates, edge-folding blades carried by said arms adapted to be thrown toward each other, as said arms approach their highest positions, and means for holding said blades so that as they descend they will be held parallel to each other, and a pivoted folding member carried by each arm, as set forth.

19. A wrapping-machine, comprising in combination with the frame, the driving-shaft, cam-wheel rotating therewith, the horizontally-movable folding-blades, levers contacting with said cam-wheel for operating said folding-blades, a reciprocating cross-head and connections between same and the cam-wheel, the pivoted arms carried by the cross-head, and rocked or tilted as said cross-head reciprocates, a blade carried by each of said arms, which blade is adapted to fold the opposite edges of the wrapper, and retaining guide-plates held to the frame of the machine behind which said edge-folding blades are adapted to engage, and be held in parallel relation against the article to be wrapped as said blades are descending, and a pivoted folding-flap carried by each arm, as set forth.

20. A wrapping-machine, comprising in combination with the frame, the driving-shaft and cam-wheel rotating therewith, a reciprocating cross-head, the horizontally-reciprocating folding-blades, the pivoted arms carried by the cross-head, a blade adapted to fold the opposite edges of the wrapper carried by each of said arms, means for throwing said edge-folding blades toward each other as the cross-head is driven to its highest position, stationary retaining guide-plates, behind which said cross-head is thrown, a pivoted folding member on each of said arms and having a projection which is adapted to fold the top flaps slightly in advance of the folding of the edge flaps, and means for throwing said pivoted folding member outward, as the opposite edge flaps are folded, as set forth.

21. A wrapping-machine, comprising in combination with the frame, the driving-shaft and cam-wheel rotating therewith, the horizontally-movable folding-blades, means for actuating same, the reciprocating cross-head, pivoted arms carried thereby, and means for tilting the same as the cross-head reciprocates, folding-blades secured one to each arm, which blades are adapted to fold the opposite edges of the flap, one in advance of the other as said blades are held in parallel relation, and

on their downward movement, a pivoted folding member on each of said arms, a stationary portion of the frame in the path of said pivoted folding member adapted to throw the latter outward as the opposite edge flaps are being folded, as set forth.

22. A wrapping-machine, comprising in combination with the frame, the operating-shaft and cam-wheel rotated therewith, the horizontally-movable folding-blades and means for operating the same, the cross-head, connections between same and the operating-shaft, the pivoted arms carried by the cross-head, means for tilting said arms as the cross-head reciprocates, the edge-folding blades and pivoted folding member carried by each of said arms, means for adjusting said edge and top folding members longitudinally on each of said arms, as set forth.

23. A wrapping-machine, comprising in combination with the frame, the operating-shaft, a reciprocating cross-head, pivoted arms carried by said cross-head, means for imparting an intermittent motion to the cross-head as the shaft is rotated.

24. A wrapping-machine, comprising in combination with the frame, the driving-shaft, a reciprocating cross-head, and means connected with said shaft for operating same, pivoted arms carried by said cross-head, and means for throwing the upper ends of said arms toward each other when the cross-head is at its upper end, and stationary, as set forth.

25. A wrapping-machine, comprising in combination with the frame, the driving-shaft, the cam-wheel, a reciprocating cross-head, the horizontal folding-blades, means for operating the same, a sliding plate carried by the cross-head, and having pitman and lever connections with said cam-wheel, the pivoted arms, and means for actuating same as said plate slides, as set forth.

26. A wrapping-machine, comprising in combination with the frame, driving-shaft, cam-wheel rotating therewith, a reciprocating cross-head, a sliding plate secured to said cross-head, and having a longitudinal play, pivoted arms carried by the cross-head, a pivoted and tilting link actuated by said sliding plate, and adapted to operate said pivoted arms as the cross-head and plate carried thereby are reciprocated.

27. A wrapping-machine, comprising in combination with the frame, the driving-shaft and cam-wheel rotating therewith, a reciprocating cross-head, a plate having a longitudinal sliding connection with said cross-head, pitman and lever connections between said plate and the cam-wheel, the arms carried by the cross-head, and having their lower ends angled, one of said angled ends being concaved to receive the convex end of the other, and adapted to tilt in contact with each other, and a link adapted to tilt one of said levers, as set forth.

28. A wrapping-machine, comprising in combination with the frame, the driving-shaft

and cam-wheel rotating therewith, the reciprocating cross-head adapted to be stationary for a moment when at its highest limit and sliding plate mounted thereon, pitman and lever 5 connections between said cam-wheel and the sliding plate, the arms carried by the cross-head and having their lower portions angled, one end being concaved and the other convex, and held in contact with each other, a link 10 mounted on one of the pivots of said arms, and having pivotal connection with the angled portion of one of said arms, whereby as said sliding plate is reciprocated independent of the cross-head, said arms are tilted upon their pivots, 15 as set forth.

29. A wrapping-machine, comprising in combination with the frame, a driving-shaft, reciprocating cross-head, a sliding plate mounted thereon, connections between said 20 sliding plate and the driving-shaft, the pivoted arms carried by the cross-head, and having their lower ends angled and turning in contact with each other, one of the meeting ends of said arms being concaved to receive 25 the convex end of the other, shoulders on said ends to limit the throw of said arms, a link carried on one of the pivotal pins of said arms, and having pivotal connection with the angled portion of an arm, and its free end engaging 30 a recess in said sliding plate, as set forth.

30. In a wrapping-machine, the combination with the frame, the shaft, the reciprocating cross-head, the sliding plate having 35 slots at its opposite ends, screws secured to the cross-head and passing through said slots to limit the throw of said plate, the arms pivoted at their angled portions to the cross-head, the inner ends of said arms, being held 40 in frictional contact, shoulders to limit the throw of said arms, and slotted guide-plates through which the arms pass, a link mounted on one of the pivots of said arms and having pivotal connection with the angled end of one 45 of said arms, the end of said link adapted to rest in a recess in said sliding plate, and to be tilted by the latter as the plate reciprocates independent of the cross-head, as set forth.

31. In a wrapping-machine, the combination with the frame, the driving-shaft, the cam-wheel rotating therewith, the cross-head, the pivoted arms carried thereby, sliding plate mounted upon the cross-head, means for tilting said arms as the plate moves independent of the cross-head, a slotted lever C⁷ 55 pivoted at one end to the frame of the machine, pitman connection between said lever and sliding plate, and a pin C⁵ mounted eccentrically on said cam-wheel and working in the slot of said lever, whereby the cross-head has an accelerated motion during its upward movement, and a gradual movement on the downward throw of said cross-head, as set forth.

65 32. A wrapping-machine, comprising in combination with the frame, the driving-shaft and cam-wheel rotating therewith, a recipro-

cating cross-head, sliding plate mounted thereon, pivoted arms carried by the cross-head and means for tilting said arms as said 70 plate is actuated independent of the cross-head, a slotted lever pivoted to the stationary portion of the frame, a wrist-pin carried by the cam-wheel and having a sliding play in said lever, and pitman connection between 75 said sliding plate and lever, as set forth.

33. A wrapping-machine, comprising in combination with the frame, the driving-shaft, cam-wheel rotating therewith, a segment-cam mounted on one face of the cam-wheel, the pivoted levers L and V, the folding-blades actuated by said levers L and V, the paper-guiding plate mounted on the table, a pivoted lever K² actuated by said lever L for reciprocating said guide-plate. 85

34. A wrapping-machine, comprising in combination with the frame, driving-shaft, the cam-wheel rotating therewith, the lever V normally held in contact with the cam edge of said wheel, a horizontal folding-blade having a bar V⁵ engaging an aperture in the upper end of said lever, a spring V⁷ secured to said bar and a pin V⁸ secured to the free end of said spring, and adapted to slide in diagonally-disposed slots V⁹ in the frame of the machine, whereby as said horizontal blade is drawn forward, the spring will be slightly under tension, and the folding-blade adapted to yield slightly, as set forth. 90

35. A wrapping-machine, comprising in combination with the frame, the driving-shaft and cam-wheel mounted thereon, a segment-cam on the face of said cam-wheel, the pivoted lever L actuated by said segment-cam, a spring mounted on the pivotal pin of said lever, one end bearing against the stationary part of the frame, its other end against a pin on said lever, and adapted to normally hold the lower concaved portion of said lever in the path of the circumference of said segment-cam, a pin carried at the upper end of said lever, the folding-blade secured to said pin and a spring secured to said blade, and a tilting lever slotted, and engaging said pin, and a paper-guide plate actuated by said tilting lever, as set forth. 105 110 115

36. In a wrapping-machine, the combination with the frame, the driving-shaft, the cam-wheel, a reciprocating cross-head, a sliding plate mounted on said cross-head, pivotal connections between the cam-wheel and said plate, and a spring bearing against the cross-head and adapted to frictionally engage and hold the same suspended while said plate has a movement independent of the cross-head, 120 as set forth. 125

37. A wrapping-machine, comprising in combination with the frame, the driving-shaft, the cam-wheel mounted thereon, the segment-cam, the pin mounted on said segment, the tilting lever actuated by the segment-cam, and the folding-blade actuated by said lever, a plunger, a spring-actuated pivoted lever having connection with said plunger, a trip 130

member pivoted to the frame and having link connections with said plunger-engaging lever, the lower end of said trip disposed in the path of said pin on the segment-cam, whereby the 5 plunger is drawn forward and automatically returned to its starting position by said spring-actuated lever, as set forth.

38. A wrapping-machine, comprising in combination with the frame, the driving-shaft 10 and cam-wheel, the plunger, the table on which the same is mounted, the spring-actuated lever engaging said plunger, the pivoted trip, link connection between the same and said lever, the pin mounted on the cam-wheel 15 adapted to contact with said trip to drive the plunger forward, said plunger being longitudinally slotted, a spring secured to the frame and having its lower free end engaging in the slotted end of said plunger, as set forth.

20 39. A wrapping-machine, having in combination with the frame, the driving-shaft, the cam-wheel mounted thereon, the plunger and folding means, and mechanism for operating

the same, the folding-table having diagonally-disposed and slightly-curved slots in its opposite edges, one in advance of the other, and into which the last flaps of the wrapper are adapted to engage as the articles being wrapped are successively driven by the plunger outward, the outer marginal walls of said 25 slots projecting outward over the opposite sides of the table, forming wings to guide the end flap, as set forth.

40 40. In combination with the cross-head and pivoted arms carried thereby, the folding-blade S secured to each arm, said plate having its lower end slotted, one edge of which is provided with an abrupt curved portion T, and its opposite edge curved gradually, as set forth.

In testimony whereof I hereunto affix my signature in presence of two witnesses.

JOHN H. FELMLEE.
